SEMAUTOMATIC APPARATUS FOR ELECTROPERFORATING SHOES OR THE LIKE

John W. Meaker, New York, N. Y.

Application April 9, 1947, Serial No. 740,416

5 Claims.

(Cl. 219—19)

1

This invention relates to a semi-automatic machine for electro-perforating shoes or similar articles of various sizes and shapes.

Attempts have been made to design a fully automatic machine for electro-perforating shoes, but due to many variable factors involved, such as the sizes and shapes of shoes, the variations in trimmings, variations in the density and fiber structure of the leather or other material from which shoes are made, etc., such automatic machines have not proven to be satisfactory for general use. It is an object of the present invention to provide a machine for electro-perforating shoes that is satisfactory for general use on all types of shoes where the operation of the machine is under the control of the operator at all times and by means of which the treatment of the shoe may be rapidly and effectively accomplished.

A further object of the invention is to provide a machine for electro-perforating ready-made shoes ranging from the smaller women's and children's sizes to the largest men's sizes that may be used for any shape of shoe or with any style of lacing, straps or other trimmings. Another object is to provide such a machine wherein the surface of the shoe that is treated may be selected by the operator and where the entire area to be treated will be readily accessible to the operator. A further object is to provide a machine of this character in which the operator can readily control the intensity of the electro-perforating discharge for various portions of a shoe or for different shoes as required for the material from which the shoes are made.

Still further objects and advantages of the invention will be apparent and be best understood from the following description and the accompanying drawings in which:

Fig. 1 is a side view in partial section of an electro-perforating apparatus embodying the invention;

Fig. 2 is a plan view of the electro-perforating apparatus shown in Fig. 1 with the article being perforated omitted for purposes of clarity;

Fig. 3 is an end view in partial section of the upper portion of the apparatus illustrated in Figs. 1 and 2;

Fig. 4 is a schematic wiring diagram for the apparatus shown in Figs. 1 and 2;

Fig. 5 is a side view of an inner electrode.

Fig. 6 is a side view of a portion of a somewhat modified inner electrode.

Referring to the drawings in detail, there is a platform 10 of insulating material on which a

shoe 11 or other article to be perforated may be held by any suitable means. In the illustrated embodiment, the shoe 11 is held between a heel plate 12 and a movable toe piece 13 which are secured to the platform.

The toe piece 13 is slidably mounted in a slot 14 in the platform so that it may be moved to different positions to accommodate various sizes of shoes. The toe piece 13 is resiliently urged toward the heel plate 12 and into engagement with the toe of the shoe 11 by a spring 15 having one end secured to the toe piece 13 and its other end secured to the platform.

The platform 10 is supported on a rock shaft 16, the ends of which are journalled or pivoted in supports or brackets 17 extending from a base 18. A handle 19 is secured to one end of the rock shaft 16 by means of which the platform 10 and the shoe 11 carried thereon may be rocked about a horizontal axis so as to present the sides of the shoe 11 in a convenient and accessible position to the operator of the machine. In lieu of the platform 10, as illustrated, a square box having heel and toe clips mounted on two, three or four sides may be mounted on the rock shaft 16 so that a number of shoes may be placed on the machine and removed therefrom at the same time although they would be treated individually.

An electrode 20 is located inside of the shoe 11 and is pneumatically held in firm contact with the inner surface of the shoe by a bladder 21. The bladder 21 may be made of rubber and may be shaped generally to fit the inside of a shoe when it is inflated. The electrode 20 is a sock-like member knit of a metallic thread or yarn such as silver, cordinet thread. A metallic yarn of this type is composed of a number of fine wires twisted together and has been found to be sufficiently flexible for knitting purposes. This knitted, sock-like electrode is close meshed and is expandable in both length and diameter. Such an electrode is an excellent conductor of electricity and its mesh when knit with the usual stitch is sufficiently close so that an electric discharge may be passed through the material of the shoe at practically any point to such an electrode.

The bladder 21 may be inflated by any suitable means, a ball hand pump 22 suitable for this purpose being illustrated. The bladder is also provided with an air release valve 23 so that it may be readily deflated to permit easy removal of the electrode from the shoe. In placing the electrode in the shoe, the bladder 21 may be

55

first inserted in the sock-like electrode 20 and partially inflated to support the electrode as it is being placed inside of the shoe. In this connection it may be found helpful and desirable in some instances to place a stiffening member inside of the bladder or inside of the sock-like electrode in addition to the bladder to support the electrode and bladder while being inserted inside of the shoe. After the sock-like electrode and the bladder have been placed inside of the shoe, the bladder is then inflated so as to expand the electrode and urge it into intimate contact with the inner surfaces of the shoe. As the bladder is inflated, it will expand in all directions until it fills the inside of the shoe and it will therefore force the electrode into contact with all of the contours of the inner surface of the shoe including curved surfaces such as those around the instep. It will be understood that the use of the term "pneumatic" is intended to apply to inflation of the bladder by water or other means as well as air.

While an individual, expandible, sock-like electrode 20 and its bladder 21 will fit a considerable range of sizes and shapes of shoes, it is probable that the individual electrode and bladder will not fit all sizes and shapes of shoes and there may be provided several such electrodes and bladders in such sizes as are necessary to fit the various sizes and shapes of shoes that are to be treated.

While the knit sock-like electrode and pneumatic bladder have been found to be most satisfactory, other forms of inner electrode may be used in the machine if desired. For example, the sock-like electrode may be fitted over a foot-shaped piece of sponge rubber or other material so that it may be compressed to the appropriate size and shape as it is placed inside of the shoe. The inner electrode 20 is connected to one side of a suitable source of electrical energy for a discharge circuit. In the apparatus illustrated, the inner electrode 20 is electrically connected through a series of current-limiting fixed resistances 24 to one side of a six thousand to eight thousand volt secondary of a stepup transformer 25. The connection to the electrode 20 may be made by a detachable spring clip 26 so that one electrode may be readily disconnected and another connected as desired. The other side of the secondary of the transformer is electrically connected to an electrode 27. The electrode 27 is supported at the end of a handle or wand 28 of insulating material so that the electrode may be manually manipulated. The electrode 27 is secured to the handle 28 so that an elongated, flat side is in position to be passed over the outer surface of the shoe. A roller 29 may be placed on the flat side of the electrode so that it will move over the surface of the shoe easily without scratching or marring it.

The primary of the transformer 25 may be connected to a suitable source of electrical energy, such as the usual 110-120 volt, 60 cycle alternating current, by means of an electrical connector or plug 30 that fits any usual electrical outlet. In the circuit with the primary of the transformer, there is a pair of switches 31 and 32, a variable resistance 33 and a fuse 34. The switches 31 and 32 are located, respectively, in the rock shaft handle 19 for turning the shoe platform and in the handle of the wand 28 carrying the manually manipulated electrode. These switches are of the type that are normally held open by spring action and both of which must be depressed by the operator to complete the

circuit when he operates the machine. This provides a human interlock safety feature since the operator must use both hands to close the circuit to the primary of the transformer and the instant either hand is released from operating position, the circuit is opened and the current is shut off.

The variable resistance 33, the transformer 25 and the series of fixed resistances 24 may be mounted inside of the base 18 with their appropriate wiring connections. This provides a self-contained unit that may be readily moved from place to place and set up wherever desired. The variable resistance 33 is provided with a knob 35 by means of which the resistance may be adjusted by the operator so as to control the current to the transformer and thus the intensity of the discharge between the electrodes in accordance with the grade and types of material that is being perforated.

To operate the machine, the operator grasps the handle 19 of the rock shaft and depresses the switch 31 therein with one hand while he holds the wand 28 carrying the electrode 27, and depresses the switch 32 therein with the other hand. The operator then passes the electrode 27 over the surface of the shoe. As discharges occur between the electrodes, they can be readily observed by the operator and he is able to judge by the appearance of the arc and the number of discharges which appear to be going through the leather or other material, just how to maneuver the electrode or to adjust the current for proper results. The operator then guides the electrode over areas where perforations are desired and avoids areas which are not to be perforated, for example, the trimmings and stitched areas. If the desired perforation of a given area proves to be more difficult than other areas, the operator can either pass the electrode over such areas several times to obtain the desired perforations or he can increase the intensity of the discharge by regulating the current.

The complete perforation of a shoe can be carried out very rapidly with such a machine when operating with the ordinary 60 cycle alternating current as there will be in the order of 120 discharges passing through the shoe each second so that a shoe may be satisfactorily perforated in from twenty to thirty seconds.

A somewhat modified sock-like electrode 36 is illustrated in Fig. 6. This electrode is similar to the previously described electrode except that there is a toe section 37 knit of ordinary yarn in order that the electrodes may be knit by machine. The same may also be true of the heel and top of the electrode. However, this does not affect the operation or function of such an electrode particularly since these portions of the electrode are generally located inside of the shoe where perforation is either not possible, as under the box toe, or necessary.

While a preferred embodiment of the invention has been described and illustrated herein, it will be understood by those skilled in the art that various changes and modifications may be made without departing from the scope of the invention as defined by the appended claims.

I claim:

1. In an apparatus for perforating articles of wearing apparel of various sizes and shapes having recessed interiors by an electrical arc discharge, the combination of an expandible electrode shaped to fit inside of an article of wearing apparel, pneumatically inflatable means fit-

ted within the expansible electrode for expanding the electrode carried thereon and maintaining said electrode in contact with the inner surface of said article, a second electrode located on the outside of said article and having a smaller discharge surface area than the first-mentioned electrode, said second electrode being engageable with a limited area on the outer surface of the article and movable independently of the expansible electrode over the outer surface of the article in opposed relation to the expansible electrode, a platform supporting the article with the expansible electrode and the inflatable means inside thereof, said platform and the article supported thereon being movable relative to the second electrode, and a circuit connecting said electrodes to a source of high voltage electrical current, said current being capable of passing an electrical arc discharge between the electrodes and through the article.

2. In an apparatus for perforating articles of wearing apparel of various sizes and shapes having irregularly shaped, recessed interiors by an electrical arc discharge, the combination of an expansible electrode shaped to fit inside of an article of wearing apparel, said electrode being knit from an electrically conductive yarn and conforming to the contour of the inside of the article when expanded, an inflatable bladder fitted within said electrode, said bladder when inflated expanding the electrode supported thereon and maintaining said electrode in contact with the inner surface of the article, a second electrode located on the outside of the article, said second electrode having a discharge surface area smaller than the surface of the expansible electrode and being movable independently of the expansible electrode over the outer surface of the article in opposed relation to the expansible electrode, a platform supporting the article with the expansible electrode and the bladder inside thereof, said platform and the article supported thereon being movable relative to the second electrode, and means for supplying a high voltage electrical current connected to the electrodes capable of passing an electrical arc discharge between the electrodes and through the article.

3. In an apparatus for perforating by an electrical discharge articles of wearing apparel of various sizes and shapes having recessed interiors, the combination of an expansible electrode shaped to fit inside of an article of wearing apparel, pneumatically inflatable means fitted within said electrode, hand operated means for expanding the inflatable means and the electrode supported thereon into contact with the inner surface of said article, a platform supporting the article with the expansible electrode and the inflatable means inside thereof, a second electrode located on the exterior of the article, said second electrode having a discharge area smaller than the expansible electrode and being movable independently of the expansible electrode over the outer surface of the article in opposed relation to the expansible inner electrode, means for moving said platform and the article supported thereon relative to the second electrode and a circuit connecting said electrodes to a source of high voltage electrical current capable of passing an

electrical arc discharge between the electrodes and through the article when the electrodes are in opposing relation on opposite sides of the article.

5. In an apparatus for perforating a shoe by electrical arc discharges, the combination of an expansible inner electrode located inside of a shoe, said electrode having a sock-like shape and being knit of an electrically conductive yarn, an inflatable bladder located inside of said expansible electrode, said bladder being shaped to fit within said electrode, means for inflating said bladder and expanding the electrode supported thereon into contact with the inner surfaces of the shoe, a second electrode located on the outside of the shoe and having a discharge area smaller than the surface of the expansible electrode, said second electrode being movable over the outer surface of the shoe independently of 10 and in opposed relation to the expansible electrode, a platform supporting the shoe with the expansible electrode and bladder inside thereof, said platform and the shoe supported thereon being movable relative to the second electrode, 15 and a circuit connecting said electrodes to a source of high voltage electrical current, said current being capable of passing an electrical arc discharge between the electrodes and through the shoe.

30. 6. In an apparatus for perforating a shoe by electrical arc discharges, the combination of an expansible inner electrode located inside of a shoe, said electrode having a sock-like shape and being knit of an electrically conductive yarn, an inflatable bladder located inside of said expansible electrode, said bladder being shaped to fit within said electrode and supporting said electrode in contact with the inner surfaces of the shoe when inflated, a second electrode located on the outside of the shoe, said second electrode being manually movable over the outer surface of the shoe independently of and in opposed relation to the expansible electrode located inside of the shoe, a circuit connecting said electrodes to a 35 source of high voltage electrical current, said current being capable of passing an electrical arc discharge between the electrodes and through the shoe, a platform supporting the shoe with the expansible electrode located inside thereof, said platform being rockable for moving the shoe supported thereon relative to the second electrode.
